United States Patent Office

Des. 214,641
Patented July 8, 1969

214,641

HOLDER FOR A PLATE AND BEVERAGE CUP OR THE LIKE

Irving Malakoff, 2000 Linwood Ave.,
Fort Lee, N.J. 07024

Filed July 24, 1968, Ser. No. 12,881

Term of patent 14 years

Int. Cl. D8—02

U.S. Cl. D44—29

FIG.1

FIG. 4

FIG. 1 is a perspective view of a holder for a plate and beverage cup or the like showing my new design;

FIG. 2 is a top plan view;

FIG. 3 is a side elevational view; and

FIG. 4 is a bottom plan view.

The cup and plate shown in broken lines in FIG. 3 are for illustrative purposes only.

I claim:

The ornamental design for a holder for a plate and beverage cup or the like, substantially as shown and described.
